UNITED STATES PATENT OFFICE.

GAUTIER A. CHRISTOPHERSON, OF SAN FRANCISCO, CALIFORNIA.

PAPER-HANGER'S KNIFE ATTACHMENT.

Application filed August 17, 1925. Serial No. 50,880.

To all whom it may concern:

Be it known that I, GAUTIER A. CHRISTOPHERSON, a citizen of the United States, and a resident of San Francisco, in the county of San Francisco and State of California, have invented a new and useful Paper-Hanger's Knife Attachment, of which the following is a specification.

The general object of the invention is to provide an adjustable guard for the blade of a paper hanger's knife, and to adapt the guard to guide the blade when trimming wall paper transversely or longitudinally to fit into the corners of a room, or upon the top of a baseboard, or around a door casing.

The invention further proposes to adapt the guard to provide means for forcing the paper into the corner between two adjacent walls simultaneously with the cutting of the paper, and also to adapt the guard or cooperate with the knife blade to function as a slitting shear.

The invention still further proposes to provide a device that is adapted for easy attachment to the standard form of paper hanger's knife.

The above objects are secured in the device illustrated in the accompanying drawing and in which:—

30 Figure 1 is a side elevation of my device in position on a paper hanger's knife;

Figure 2 is a bottom view thereof;

Figure 3 is an end view of Figure 1; and

35 Figure 4 is a transverse section taken along the line 4—4 of Figure 1.

Briefly described, my invention comprises a device or attachment which clamps to the handle of a paper hanger's knife and functions as a smoothing guard for pressing wall

40 paper into a corner of the wall being papered and cutting the paper along the corner; also such a device which is adjustable relative to the blade of the knife to compensate for wear thereof and also to function with the knife blade as a pair of slitting shears.

In the drawing a paper hanger's knife is shown having a blade 1 secured to a round handle 2 and with my attachment secured by a yoke 3 clamped around the handle by means of a screw 4.

This yoke is split to fit handles of slightly varying diameter, and has a pair of dependent ears 5 against the sides of which the body of my device clamps by a relatively

55 large screw or rivet 11 so as to secure a very firm frictional joint thereon.

The body of the device comprises a pair of guards or jaws 6 extending along both sides of the blade, exposing its cutting edge at 1', and having a rounded connecting web 60 at 7' terminating at 7" extending over the rear portion of the cutting edge of the blade.

The jaws taper forwardly and as seen in Figure 4 also taper downwardly and in the sectional view are shown to include in their 65 downwardly tapering form less than a right angle so that when pressed into a corner of the wall the jaws will not strike the walls of the room to thereby interfere with the knife blade cutting the paper in the extreme corners but will guide the blade against both angles of the wall and permit working in narrow angle corners or unusual depressions in ordinary corners.

In using the tool it is gripped by the handle and drawn in a direction away from the blade while pressing the rounded web 7 against the paper to force it into the corner continually in advance of the cutting portion of the blade, the paper lying in a 80 relative plane as indicated by the line A—A.

The guard is adjustable to cooperate with different sized blades and to compensate for wear on the part of the blade with which it may be used. In this connection a screw 85 8 is provided which is adjustable through a nut 9 fixed to the shank of the device and having a head bearing against a portion of the handle or clamp, while a hole 10 in the shank permits passage of the screw end.

The screw is more easily adjusted by simply winging the device away from the blade on its pivotal joint 11, and when sharpening the blade the device is swung clear back along the handle as indicated by the dotted 95 position "B".

The device also functions with the cutting edge of the blade to form a pair of slitting shears for the paper, a function gained by adjusting the screw 8 so that the guards 100 will only close to the position "C" so that the angular juncture of the top of the jaws and the cutting edge of the blade forms the slitting shears for pushing through the paper.

In contemplating my invention it will be seen to comprise a sheet metal device, though it is understood that any suitable construction is contemplated and any modifications in clamp or adjustment coming within the 110 spirit of the invention.

While I have described the use of my in-

vention as a paper hanger's knife, it shall be understood that by this I do not wish to be limited as, in practice, the invention may be put to many uses, such as for instance, ⁵ the cutting or ripping of oil cloth, canvas, or like materials.

I claim:

- 10 1. A device of the character described adapted for attaching to the handle of a knife, and provided with a rounding guard overhanging the edge of the knife for forcing paper into a corner in cutting the same with the knife.
- 15 2. In a device of the character described, a clamp adapted for clamping to the handle of a knife, a guard hingedly connected to the clamp, and means for adjustably limiting the hinged movement of the guard.
3. A guard for a paper hanger's knife

comprising a longitudinally tapered recessed ²⁰ portion adapted for receiving the edge portion of the knife blade, a support adapted for connection to the knife and means adjustably connecting the recessed portion to the support. ²⁵

4. A guard for a paper hanger's knife comprising a longitudinally and transversely tapered recessed portion adapted for receiving the edge portion of the knife blade, a support adapted for connection to the ³⁰ knife, means adjustably connecting the recessed portion to the support, and means carried by one of the parts and adapted to cooperate with the knife to secure the recessed portion in various positions of adjustment with respect to the cutting edge of the knife blade. ³⁵

GAUTIER A. CHRISTOPHERSON.
